CABINET TOP

Anthony P. Geimer, Two Rivers, Wis., assignor
to Hamilton Manufacturing Company, Two
Rivers, Wis., a corporation of Wisconsin

Application January 15, 1943, Serial No. 472,435

4 Claims. (Cl. 312—163)

This invention relates to cabinet top more particularly for professional cabinets such as are used by dentists and physicians.

An object of the invention is to provide an improved and simplified structure for this purpose, and this, and other objects and advantages, will be apparent from the following description, taken together with the accompanying drawings forming a part of this specification, and in which—

Figure 1 is a plan view of a cabinet top embodying the present invention, broken away to expedite description;

Figure 2 is a sectional view, somewhat enlarged, taken on the staggered line 2—2 of Fig. 1;

Figure 3 is a fragmentary sectional view, on the scale of Fig. 2, but taken on the line 3—3 of Fig. 1;

Figure 3a is a fragmentary plan view of a corner of the top, on the scale of Fig. 1, with the working top omitted;

Figure 4 is a fragmentary perspective view, on the scale of Figs. 2 and 3, of a corner of the working top shown in Figs. 1, 2 and 3;

Figure 5 is a perspective view showing a preferred assembly of a working top, frame therefor, and cabinet base, with the working top and frame therefor together in separated relation from the cabinet base but indicating by arrows the direction of movement to put the parts into assembled relation; and

Figure 6 is a separated view of the frame shown in other figures of the drawings.

Referring in detail to the illustrative construction shown in the drawings, one form of cabinet such as herein referred to, may have the usual drawer part 10, forming the base of the cabinet and elevating the top 11 of the cabinet to a height convenient for working thereon, by the dentists, for example while in standing position, and supporting the cabinet top at this height.

As disclosed in the Evans Patent No. 2,045,264 of June 23, 1936, the working top of the cabinet is conveniently comprised of two parts, namely, the top proper 11 and a medicine bottle compartment 12, separated, in one instance, by a depressible partition 13 which is lowered automatically when the cover member 13a of the bottle compartment is raised to uncover the latter, means for this co-action being described and claimed in said patent. At the ends of the bottle tray compartment 12 are the upstanding cabinet walls 13b which may support such mechanism referred to.

The cabinet top proper, with which the present invention is concerned, is, as here shown, made up of an underlying frame 14, conveniently formed at least in part of wood and carrying the working top 15 thereon. The working top 15 is desirably constructed of a solid sheet of welded or compressed fibre material or similar cellulosic composition 15a impregnated with a relatively heavy initially liquid and later baked or otherwise hardened lacquer or the like which produces thereon an acid and wear resisting coating 16 which is finally advantageously rubbed down especially upon its upper working surface 35, to provide a smooth hard finish.

To secure the working top 15 and its wood frame 14 together, the frame may carry dowels 17 sunk into mortises 17a in the frame and having upstanding ends which are received by a tight holding fit in similar mortises 17b spaced to register therewith along the under side of the outer margins of the working top. Kerfs 17c in the dowel pins facilitate a good glued connection between the dowel pins and their engaging parts in this assembly, which thus define, as so constructed and arranged, the working top 15 and its wood frame 14 as a unitary, in this instance removable, top 11 for the cabinet.

The wood frame 14 is desirably faced with a metal moulding, angle-shaped in cross-section, which thus forms a part of the frame and having the front part 18 and bottom part 19, the front part 18 constituting a facing for the outer surface of the frame 14 and the bottom part 19 constituting a facing for the under edge of the frame. As shown in Fig. 3a, the front facing part 18 of the moulding may be continuous from end to end of the frame and formed correspondingly about the curved corners 34 thereof, while the bottom facing part 19 of the moulding may be discontinued at the corners. Screws 20 are shown securing the metal moulding to the frame as by curing the metal moulding to the frame as by being received through the bottom part 19 of the moulding and screwed upwardly into the under side of the frame. Thus, the moulding 18—19 terminates below the working top 15 to expose the edge of the latter and it is also a constituent element, as here shown, of the unitary cabinet top 11 while at the same time it may be formed separately as a part of a frame therefor.

Turning now to the preferred assembly of the unitary cabinet top 11 and the cabinet base or main cabinet part, the base 10, as here shown, has a sub-top 21 thereon conveniently formed of wood and secured thereto by any suitable

means which need not be here described. In accordance with the present disclosure, however, the sub-top 21 is spaced away from the front and sides of the cabinet leaving a step 22 about the upper margin thereof, as best seen in Fig. 5. At the corners, the sub-top 21 is advantageously cut on the diagonal as at 23 to accommodate the corner construction and corresponding somewhat to the diagonal inner sides 24 of the frame 14 which fit therewith when the frame 14, with its working top 15, is assembled with the cabinet base 10.

In the illustrative construction, such assembly is desirably effected by a horizontal movement of the cabinet top 11 from front to rear of the cabinet, the frame 14 carrying another pair of fixed dowels 25, horizontal in this instance, which are received in registering sockets 26 in the cabinet ends 13b aligned with the step 22 upon which the frame slides in this assembly and upon which it is supported when pressed home with the dowels 25 snugly taking into the sockets 26.

To further secure this assembly, the sub-top 21 advantageously carries a spring clip, in this instance three such clips 27, which are secured to the vertical edge 28 of the sub-top 21 as by screws 29. The free ends of the clips 27 insure a frictional grip of the frame 14 as by taking into notches 30 spaced along the upper edge of the frame 14 beneath the element 15, in register with the clips, the outer ends of the clips being slightly upturned as at 31 to provide a frictional locking lip. Thus the cabinet top 11, comprising the working top 15 and its frame 14, are securely held on the cabinet 10 against accidental displacement, but may be readily removed as a unit when desired, as, for example, during shipments of the parts or for any other purpose, at which time the frame 14 is substantially concealed or inconspicuous by reason of the metal moulding 18-19 being a unitary part of the removable top. Also, the metal moulding 18 desirably conceals the notches 30 into which the spring clips 27 take.

Further in accordance with the present invention and turning again to the working top 15 itself, this member is importantly constructed with a shallow, relatively wide groove 32 formed in its upper surface, spaced uniformly inwardly of the edge thereof and extending along the margins of three of the sides thereof, namely, its two sides and front, and including the rounded corners 33, which correspond with the rounded corners 34 of the frame. The groove 32 adjacent the corners has a radius corresponding to the radius of the corners.

The groove 32 is such that when the initially fluid, hardenable coating 16 is superposed on the working top 15 to form a surface thereon and particularly the upper polished working surface 35, the coating flows into the groove to form the inclined walls 36, desirably merging as by relatively imperceptible graduations into the working surface 35, thus not only avoiding sharp edges thereat but permitting the coating to flow conveniently thereto, and, after hardening of the latter, facilitating easy cleaning of the groove. As clearly shown in the drawings, the groove 32 is of substantially less depth than width.

The groove 32 insures that liquids, sometimes such as acids, spilled on the cabinet top will not run down the side of the cabinet to mar or damage it, but will run into the groove and be retained therein until removal is convenient. Furthermore, instruments and small parts commonly

used in dental offices, such as burrs and small pieces of metal for inlays or the like, may be temporarily laid in this groove while the dentist is waiting to work therewith and will not roll around or off the working surface.

The invention is not intended to be limited to details of construction shown for purposes of exemplification, and furthermore, it is not essential that all features of the disclosure be used jointly, as various sub-combinations may at times be advantageously employed.

What is here claimed is:

1. In a structure of the class described, the combination with a cabinet base, of a flat sub-top forming a part of the base, a recess about the front and two sides of said base adjacent said sub-top providing a step thereat, a frame received on said step about the margin of said sub-top, a working top carried on said frame covering said sub-top, said frame terminating below said working top to expose the edge of said working top, said working top comprising a layer of non-metallic material provided with a shallow relatively wide groove extending along the front and side margins of said working top, means releasably retaining the said frame on said base, and other means retaining the working top on said frame.

2. The structure of claim 1 wherein the base and frame are provided with a pair of horizontally extending inter-engaging members aligned with said recess at each side of the base and the vertical edge of said sub-top at the front of the base carries a spring clip having a forwardly projecting spring lip, and the said frame has a notch in its upper edge below said layer of non-metallic material slidably receiving said locking lip to releasably lock the frame to the base.

3. In a structure of the class described, the combination with a cabinet base, of a flat sub-top forming a part of the base, a recess about the front and two sides of said base adjacent said sub-top providing a step thereat, a frame received on said step about the margin of said sub-top, a working top carried on said frame and sub-top covering said sub-top, said frame terminating below said working top to expose the edge of said working top, said working top comprising a layer of non-metallic material provided with a shallow relatively wide groove extending along the front and side margins of said working top, said groove being of substantially less depth than width and the said layer of non-metallic material having superposed on its upper surface including said groove an initially-fluid hardened coating, the walls of said groove being gradually inclined to permit the coating to flow thereto and to facilitate cleaning of the groove.

4. In a structure of the class described, the combination with a cabinet base, of a flat sub-top forming a part of the base, a recess about the front and two sides of said base adjacent said sub-top providing a step thereat, a frame received on said step about the margin of said sub-top, a working top carried on said frame and sub-top covering said sub-top, said frame terminating below said working top to expose the edge of said working top, said frame being in part of non-metallic material and being provided with a metal molding providing a facing for the non-metallic part of the frame and said molding concealing a notch in the cabinet base for a locking lip.
